DESIGN.

E. FLETCHER.

TONE ARM FOR PHONOGRAPHS.
APPLICATION FILED AUG. 15, 1921.

59,832.

Patented Nov. 29, 1921.

Inventor,
Elmer Fletcher
By Fred Gerlach Atty.

UNITED STATES PATENT OFFICE.

ELMER FLETCHER, OF CHICAGO, ILLINOIS, ASSIGNOR TO FLETCHER-WICKES CO., OF CHICAGO, ILLINOIS, A CORPORATION OF ILLINOIS.

DESIGN FOR A TONE-ARM FOR PHONOGRAHS.

59,832.

Specification for Design.

Patented Nov. 29, 1921.

Application filed August 15, 1921. Serial No. 492,525. Term of patent 14 years.

To all whom it may concern:

Be it known that I, ELMER FLETCHER, a citizen of the United States, residing at Chicago, in the county of Cook and State of Illinois, have invented a new, original, and ornamental Design for Tone-Arms for Phonographs, of which the following is a specification, reference being had to the

accompanying drawing, forming a part thereof.

In the drawing; the figure is a perspective of a tone-arm embodying the new design.

I claim:

The ornamental design for a tone arm for phonographs as shown.

ELMER FLETCHER.
